SPARK PLUG

William Harper, Jr., Port Washington, N. Y., assignor to H. B. Motor Corporation, New York, N. Y., a corporation of New York

Application May 25, 1937, Serial No. 144,575

7 Claims. (CL. 123—169)

This invention relates to spark plugs and aims to provide a spark plug of great durability and to increase the efficiency in smoothness of operation of internal combustion engines.

5 In accordance with the invention, these objects, as well as other advantages, are attained by providing means for creating a zone of relatively low pressure at the point of ignition. This facilitates the passage of the spark between the electrodes and also places in the spark gap the molecules of the mixture which kindle most readily and thus increases the effectiveness and rapidity of the ignition. The zone of low pressure is created by a reduced flow orifice surrounding the 10 spark gap and also by a swirling of the mixture within the ignition chamber. Both the orifice and the swirling are also of value in protecting the insulation of the spark plug from excessive heat and thus increasing its durability.

20 An illustrative spark plug embodying my invention is shown in the accompanying drawing, in which:

Fig. 1 is a side view partly in axial section;

Fig. 2 is a bottom or inner end view, and

25 Fig. 3 is a section on the line 3—3 of Fig. 1, looking in the direction of the arrows.

The spark plug shown in the drawing includes an insulator 11 of ordinary construction, a metal body 12 of special construction and two electrodes 30 10, 21. The body 12 has a nut portion 15, an externally threaded tubular portion 16 which extends well beyond the inner end of the insulator 11, and a shield portion 17 which substantially 35 closes the inner end of the tubular portion but contains passages hereinafter described. The body 12 supports the insulator 11 in the usual manner, a nut 13 being used to secure the insulator to the body. The tubular portion 16 and the shield portion 17 of the body provide a 40 chamber 14 enclosing the inner end of the insulator 11 and the spark gap 22 provided between the electrodes 10 and 21. The spark gap is at an intermediate point on the axis of the chamber 14 but near the inner end of the chamber. An 45 annular projection 18 on the inner wall of the chamber 14 divides the chamber into an inner portion 14¹ and an outer portion 14² connected by an orifice 19 of reduced diameter.

When the spark plug is mounted in an engine 50 cylinder or head in the usual manner, the inner portion 14¹ of the chamber 14 is in communication with the cylinder through passages or bores 23 in the shield 17. The mixture which flows into the ignition chamber through these passages during the compression stroke of the engine is forced

through the orifice 19 in passing from the lower portion 14¹ to the upper portion 14² of the chamber. It, therefore, flows more rapidly in the orifice than in the other parts of the chamber and thus creates a zone of relatively low pressure at the orifice which surrounds the spark gap. 5 Most desirably, the passages 23 are inclined as shown so that they enter the lower portion 14¹ of the chamber tangentially causing a rapid swirling of the mixture as it enters and passes upward in the chamber. The centrifugal effect of this swirling reduces still further the pressure at the spark gap 22 as compared with that at the circumferential parts of the chamber. The swirling is nowhere obstructed as both the electrodes 10 and 21 lie on the axis of the chamber. 10 The spark between the electrodes 10 and 21 occurs in the zone of lowest pressure and rapidly ignites the mixture in the chamber 14. The burning mixture in the chamber is projected in 15 jets through the passages 23 into the main body of the mixture which is thereby rapidly ignited. The "explosion pressure" developed in the cylinder on complete ignition of the mixture momentarily causes burning gas to flow into the 20 chamber 14 through the passages 23. This hot gas swirls about the lower part 14¹ of the chamber and then rises still swirling along the wall of the upper part 14² of the chamber before it strikes the insulator 11. It thus traverses a 25 long path over thick metal parts adapted to conduct away heat before it strikes the insulator. In this way, the portion of the insulator in the chamber is well protected against excessive heating. 30

The portion of the insulator 11 in the chamber is well protected against excessive heat, as no radiant heat can reach it from the cylinder and as the hot mixture entering through the passages 23 swirls about in the lower part 14¹ of the 35 chamber and then rises along the wall of the upper part 14² of the chamber before it strikes the insulator. It thus traverses a long path over thick metal parts adapted to conduct away heat before it strikes the insulator. 40

What I claim is:

1. A spark plug comprising an insulator, a body supporting the insulator and forming a casing providing a chamber enclosing the inner end of the insulator and containing passages entering 50 the inner end of said chamber, electrodes providing in the chamber a spark gap extending lengthwise of the chamber, and means other than said electrodes providing in the chamber a reduced orifice surrounding the spark gap. 55

2. A spark plug comprising an insulator, a body supporting the insulator and forming a casing providing a chamber enclosing the inner end of the insulator and containing passages entering the inner end of said chamber, electrodes providing in the chamber near the inner end thereof a spark gap extending lengthwise of the chamber, and means other than said electrodes providing in the chamber a reduced orifice surrounding the spark gap.
3. A spark plug comprising an insulator, a body supporting the insulator and forming a casing providing a chamber enclosing the inner end of the insulator and containing passages entering the inner end of said chamber tangentially, electrodes providing a spark gap in the chamber, and means providing in the chamber a reduced orifice surrounding the spark gap.
4. A spark plug comprising an insulator, a body supporting the insulator and forming a casing providing a chamber enclosing the inner end of the insulator and containing passages entering the inner end of said chamber tangentially, electrodes providing a spark gap in the chamber on the axis of the chamber, and an internal annular projection on the casing dividing the chamber into two parts connected by a reduced orifice surrounding the spark gap.
5. A spark plug comprising an insulator, a body supporting the insulator and forming a casing providing a chamber enclosing the inner end of the insulator and containing passages entering the inner end of said chamber tangentially, electrodes providing a spark gap in the chamber, and means providing in the chamber a reduced orifice surrounding the spark gap.
6. A spark plug comprising an insulator, a metal body supporting the insulator and forming a casing providing an enclosed chamber surrounding the inner end of the insulator and containing passages, all of which enter the chamber tangentially to create therein a body of gas swirling about the axis of the chamber, a pair of electrodes lying on the axis of the chamber so as not to retard the swirling of the gas, and providing a spark gap in the chamber spaced from its inner end and on the axis of the chamber.
7. A spark plug comprising an insulator, a metal body supporting the insulator and having a tubular portion extending beyond the inner end of the insulator, a shield closing the inner end of said tubular portion and increasing in thickness from its center towards its periphery and containing passages, an axial electrode carried by said shield and extending into the tubular portion of said body, and an axial electrode carried by the insulator and opposed to said other electrode to provide a spark gap.
